UNITED STATES PATENT OFFICE.

KARL DEINLEIN, OF PILSEN, AUSTRIA-HUNGARY, ASSIGNOR TO SKODA-WERKE ACTIENGESELLSCHAFT IN PILSEN, OF PILSEN, AUSTRIA-HUNGARY, A FIRM.

GUN-CARRIAGE.

SPECIFICATION forming part of Letters Patent No. 703,900, dated July 1, 1902.

Application filed December 26, 1901. Serial No. 87,259. (No model.)

To all whom it may concern:

Be it known that I, KARL DEINLEIN, a subject of the Emperor of Austria-Hungary, residing at Pilsen, in the Province of Bohemia, 5 in the Empire of Austria-Hungary, have invented certain new and useful Improvements in Gun-Carriages; and I do hereby declare the following to be a full, clear, and exact description of the invention, such as 10 will enable others skilled in the art to which it appertains to make and use the same, reference being had to the accompanying drawings, and to letters of reference marked thereon, which form a part of this specification.

15 This invention relates to top-carriages for ordnance provided with means for checking the recoil, and according thereto such top-carriage comprises a guide for those parts that slide backward and then forward each 20 time a shot is fired and protect the recoil-checking means and its mechanism from injury by the entrance of dirt or foreign bodies and from stoppages caused by external shocks.

The top-carriage comprises a hollow body 25 that surrounds and fits with more or less play the movable part of the recoil-checking means, which is connected to the rear portion of the gun-barrel, is closed at its front end beyond the forward point of connection between the 30 gun-barrel and the recoil-checking means, and is open at the rear end. The hollow body is also provided along its upper part with a slot that extends rearward from the forward point of connection with the gun-barrel just referred to. For the purpose of guiding the 35 recoil-checking means, which partakes of the backward and forward movements of the gun, there are arranged in the hollow body rings that engage with corresponding surfaces 40 formed on the recoil-checking means throughout its entire length.

One example of a top-carriage according to this invention, in combination with a gun and its recoil-checking means, is shown in the 45 accompanying sheet of drawings, in which—

Figure 1 shows a section of the top-carriage, and the parts are in the positions they occupy before firing. Fig. 2 is a side elevation with the exception of the hollow body, 50 which is shown in section, showing the parts

in the positions they occupy after firing. Figs. 3 and 4 are vertical cross-sections corresponding to the lines A B and C D, respectively, of Fig. 1.

The top-carriage comprises a hollow body 55 d, (which in the example is cylindrical, but may be rectangular or of any other desired form,) that incloses the recoil-checking means and is so arranged that the part of the hollow body that remains at rest during the recoil 60 surrounds the part of the recoil-checking means that takes part in the recoil movement of the gun. In other respects the construction of a top-carriage according to this invention may be varied as desired, and the 65 checking of the recoil may be effected by hydraulic or other means, while the return of the gun to the firing position may be effected either by means of a power-absorbing spring or by compressed air or by other suitable means. 70 In the example shown the cylinder a of a hydraulic brake, which is connected in a suitable manner to the rear portion of the gun b, forms the part of the recoil-checking means that takes part in the recoil of the gun, and 75 the stationary part is formed by the piston-rod e, which is attached at the front to the top-carriage d and passes through a stuffing-box c of the cylinder a and the retarding-piston f. A coiled spring h, inserted between the piston 80 and the end of the cylinder, serves for returning the gun to the firing position.

The hollow body d is entirely closed at the front, but is open at the rear end, and the rear end of its upper portion is slotted from 85 the part (marked e) at which the forward end of the connection of the gun b with the movable parts of the recoil-checking means is located when the gun is at rest. This slot is preferably made as narrow as possible and 90 contains (when the gun is at rest) the connections between the gun and the recoil-checking means, the joints at each side being provided with a closure-plate i, formed of leather, sheet metal, or the like. The portion 95 of the slot which would otherwise be open during the recoil of the gun becomes covered as the gun moves backward by a covering-plate k, which is connected to the gun at m and n, so that foreign bodies, which 100

might cause damage or prevent the return of the backwardly-moved parts, are prevented from reaching the interior of the hollow body *d*. The guiding of the recoil-checking means in the hollow body *d* is effected by a number of guide-rings *j*, inserted in the hollow body and provided with ribs and grooves which fit into corresponding grooves and ribs and formed throughout the entire length of the recoil-carriage cylinder *a*.

The hollow body *d* is provided on its exterior with projections—such, for example, as trunnions—for the purpose of connecting it to the gun-carriage and is arranged to so surround the recoil-checking means as to leave more or less play, so that dents (if any) in the hollow body *d* shall not interfere with the motion of the recoil-checking means.

I claim—

20 In a top-carriage for ordnance carrying a recoil-checking means, the combination of a hollow body provided with a longitudinally-extending slot, a recoil - checking means

mounted in said hollow body, provided with a pair of projections adapted to extend 25 through said slot and engage with a gun to cause the operation of the recoil - checking means during the action of firing, a plate conforming to the top of the hollow body and adapted to be carried by the forward part of 30 the underneath portion of the gun and moving with the latter for closing the exposed part of said slot, means arranged in said hollow body and surrounding said recoil-checking means for guiding the same, and a pair 35 of V-shaped closure-plates mounted upon the hollow body and adapted to close the joint between said body and gun, substantially as herein shown and described.

In testimony that I claim the foregoing as 40 my invention I have signed my name in presence of two subscribing witnesses.

KARL DEINLEIN.
